UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

PRINTING-DEVICE SEPARATOR FOR ADDRESSING-MACHINES.

1,299,437.

Specification of Letters Patent.

Patented Apr. 8, 1919.

Application filed August 6, 1917. Serial No. 184,767.

To all whom it may concern:

Be it known that I, JOSEPH S. DUNCAN, a citizen of the United States, residing at Chicago, in the county of Cook and State 5 of Illinois, have invented certain new and useful Improvements in Printing-Device Separators for Addressing-Machines, of which the following is a specification.

This invention relates to printing machines employing separate printing devices, usually bearing addresses or similar information, which are successively delivered from a magazine to printing position beneath a platen.

15 Such machines are now extensively used for addressing periodicals and wrappers therefor. In this class of work it is extremely desirable to separate printing device bearing addresses of expiring subscriptions as soon as the last periodical which is to be forwarded thereunder or the wrapper therefor has been printed, and devices have heretofore been suggested to accomplish this result.

20 It is an object therefore of my invention to provide in a printing machine of the character described simple and effective means for automatically selecting printing devices of a predetermined class, as for example: those bearing addresses of expiring subscriptions, separating them from the remaining printing devices and delivering the two sets of printing devices to separate receptacles.

25 Further objects and advantages of my invention will be apparent as it is better understood by reference to the following specification when read in connection with the accompanying drawing illustrating the preferred embodiment thereof in which—

Figure 1 is a plan section through the machine;

Fig. 2 is a front end elevation of a portion of the machine;

45 Fig. 3 is a section on the line 3—3 of Fig. 1;

Fig. 4 is a section on the line 4—4 of Fig. 2;

50 Fig. 5 is a section on the line 5—5 of Fig. 1.

Fig. 6 is an enlarged detail in section illustrating the operation of the selector mechanism which controls the operation of the machine;

Fig. 7 is an enlarged detail in side elevation partially in section of the means for operating the selector mechanism;

Fig. 8 is a section on the line 8—8 of Fig. 10.

Fig. 9 is a section on the line 9—9 of Fig. 10.

Fig. 10 is an enlarged vertical section through the mechanism for controlling the gate in the delivery chute and

Fig. 11 is a detail in elevation of the sprocket for the gate controlling mechanism.

In the accompanying drawing I have illustrated the application of my invention to one form of addressing machine which is commonly used in the art. It is to be understood therefore that my invention is in no way limited in its application to the particular printing or addressing machine hereinafter described since obviously the structural details thereof may be varied widely so long as means is provided for advancing printing devices to printing position beneath a platen where the impression is taken.

Referring to the drawing 5 indicates in general a frame upon which the various parts of the structure are supported. A magazine 6 is mounted at the rear end of the frame 5 to support a plurality of printing devices 7. The printing devices are successively carried from the magazine, beneath an inking device 8, to printing position beneath the platen 9 by chains 10 supported and driven by sprockets 11 and sheave wheels 12 mounted on suitable shafts which are journaled in the frame 5.

The main shaft 13 which is supported in suitable bearings in the frame 5 may be driven from any source of power and is provided with cams 14 engaging rollers 15 on a platen arm 16 pivoted at 17 on the frame 5 and carrying the platen 9 at its free end. The platen arm 16 is normally held in raised position by a spring 18 (Fig. 2) secured to the frame 5 and to the platen arm and upon each rotation the shaft 13 is moved downwardly to carry the platen 9 into engagement with the impression receiving material disposed above a printing device 7 which has been previously positioned beneath the platen by operation of the chains 10.

The main shaft 13 carries a pair of cams 18 (Figs. 2 and 4) with which rollers 19 respectively engage. The rollers 19 are mount-

ed on a yoke 20 pivoted to the frame 5. As the shaft 13 rotates the yoke 20 is positively rocked on its pivot. A rod 21 is connected at one end to the yoke 20 and extends through 5 a semi-housing 22 inclosing a spring 23 which bears at one end on a shoulder 24 carried by the rod 21 and at the other against opposite end of the housing. This end of the housing is connected to an arm 25 on the 10 rocker 26 journaled on a shaft 27 which extends transversely of the machine and is supported at its ends in the frame 5.

An arm 28 on the rocker 26 extends forwardly therefrom and is provided at its end 15 with a dog 29 (Fig. 3) adapted to successively engage pins 30 on one of the sprockets 11, as the arm 28 is moved back and forth, to rotate the sprocket 11 and thereby advance the chains 10 and carry the printing 20 devices 7 from the magazine 6, step by step, to printing position. A spring arm 31 rigidly supported beneath the dog 29 serves as a support therefor when it is withdrawn for engagement with the succeeding pins 30 25 during the operation of the machine.

Arms 32 (Fig. 1) on the rocker 26 is connected by a link 33 to the frame of the inking device 8 which is provided with a rearwardly extending arm 34 (Fig. 3) connected 30 by a link 35 to the frame 5. As the rocker 26 oscillates the inking device 8 swings forwardly and backwardly to deliver ink to the printing devices and is maintained in parallel relation to the bed by the arm 35 34 and link 35.

At the forward end of the machine and in front of the platen 9 the bed of the machine slopes downwardly (Fig. 5) forming a chute 36 into which the printing device is moved 40 by the chains 10 after an impression has been taken therefrom by the platen. A gate 37 is mounted on a rod 38 pivotally supported and extending across the chute and when in the position indicated in Fig. 5 the gate directs 45 the printing devices into a branch chute 39 extending downwardly beyond the end of the chute 36 and conveniently pivoted on the frame 5 at 39'. Supported within the frame 5 and beneath the bed of the machine 50 are two trays 40 and 41, the latter being removable from the machine. These trays are arranged so that their forward ends are respectively beneath the chutes 36 and 39 to receive the printing devices delivered therefrom.

An arm 42 (Figs. 1 and 4) on the rocker 26 is connected by a bar 43 to a swinging packer frame 44 pivoted at 45 on the frame 5. The packer frame 44 is provided with 60 depending fingers 46 which enter the end of the tray 40. As each printing device is delivered to the tray the packer frame is advanced to force the printing device rearwardly in the tray past the spring pressed 65 stops 47 on the lower ends of the chute 36.

A packer frame 48 is pivoted at 45 outside the packer frame 44 and is provided with depending fingers 49 which enter the end of the tray 41. The packer frame 48 is actuated to force printing devices as received 70 rearwardly in the tray 41 past the spring pressed stops 50 on the lower ends of the chute 39 by a hook 51 pivoted to the bar 43 and having an adjustable screw 52 adapted to engage a pin 53 on the packer frame 48. 75 A spring 54 connected to the frame 5 and to the packer frame 48 causes the latter to swing upwardly when released as hereafter described. After the packer frame 48 has been advanced by the movement of the hook 51 it is returned to normal position by a spring pressed plunger 55 mounted on the packer frame 48 and engaging the chute 39.

A link 56 (Figs. 2 and 4) is pivotally connected to the hook 51 and is bifurcated at its lower end to embrace a shaft 57 rotatably mounted in the frame 5 and provided with a portion 57' adapted to engage and support the tray 41. A cam 58 on the shaft 57 is adapted to engage an ear 59 on the link 56. 85 A finger lever 60 is provided on the shaft 57 whereby the latter may be rotated at will to cause the portion 57' to engage and lift the tray 41 to operative position. At the same time the cam 58 disengages the ear 59 and permits the hook 51 to engage the pin 53. A latch 61 on the frame 5 normally holds the finger lever 60 in this position. When the latch is released the shaft 57 will 90 rotate permitting the tray to drop so that the packer frame 48 is released and permitted to swing upwardly. At the same time the hook 51 is disengaged from the pin 53.

The rod 38 which supports the gate 37 is 105 provided at one end with a yoke 65 (Fig. 8). An arm 66 is loosely mounted on the rod 38 between the arms of the yoke. An adjustable screw 67 in one arm of the yoke engages the arm 66 and a spring 68 is disposed between the arm 66 and the other arm of the yoke. A spring 69 (Fig. 2) connected to the arm 66 and to the frame 5 of the machine normally holds the rod 38 and consequently the gate 37 in the position indicated 110 in Fig. 5.

In the embodiment of my invention herein described it is desired to pass all printing devices which are to be used again through the chute 39 to the tray 41 and to deflect 120 printing devices bearing addresses of expiring subscriptions to the chute 36 and the tray 40. Obviously this plan may be reversed if desired. In the machine as shown however, it is necessary to shift the gate 37 after every impression taken from a printing device which is to be deposited in the tray 40 and to leave the gate in its normal position after each impression from a printing device which is to be deposited in the 125 130

tray 41. The selector mechanism which controls the movement of the gate 37 acts upon the respective printing devices before they reach printing position beneath the platen.

5 Consequently it is necessary to delay the operation of the gate 37 until two revolutions of the shaft 13 have ensued following operation of the selector mechanism. This permits the printing device to move from the 10 selector mechanism to printing position where an impression is taken and thence to the chutes. With this brief description of the purpose of the mechanism the structure hereinafter described will be more readily 15 understood.

A shaft 70 (Figs. 2 and 3) is rotatably mounted in the frame 5 and is driven from the main shaft 13 by a chain 71 engaging sprockets 72 on the respective shafts. The 20 sprocket 72 on the shaft 70 is secured thereto by screws 73 (Figs. 10 and 11) mounted in a cap 74 which is made fast to the shaft by a pin 75. By removing the screws 73 the shaft 70 may be rendered inoperative as 25 is sometimes desirable.

Two collars 76 and 77 (Fig. 10) are secured to the shaft 70 in spaced relation by pins 76' and 77'. A cam 78 is keyed to a reduced extension 79 of the collar 76. Cams 30 80 and 81 are loosely disposed on the shaft 70 the former between the collars 76 and 77 and the latter between the collar 77 and an adjacent portion of the frame. Normally the cams 80 and 81 are operatively connected to the shaft 70 by dogs 82 and 83 pivotally supported on the respective cams and held in engagement with notches 84 and 85 in the collars 76 and 77 by springs 86 and 87. Thus upon each revolution of the 35 shaft 13 the shaft 70 and the cams thereon will also turn through a single revolution. The cam 81 engages a roller 88 on the arm 66 and is provided with a high portion followed by a slight depression. As this high 40 portion passes the roller 88 the arm 66 causes the yoke 65 to swing, thus moving the gate 37 to the right viewing Fig. 5. The cam 81 is timed however so that normally the roller 88 rests on a low portion 45 thereof when a printing device reaches the delivery end of the machine. Therefore the printing devices will fall into the chute 39 and thence into the tray 41.

Pivoted on a transverse rod 55 89 (Fig. 3) is a rocker having a depending arm 90 which normally engages and is held from swinging movement to the right viewing Fig. 3 by the end of an arm 91 connected to the selector mechanism presently 60 to be described. An arm 92 of the rocker is connected by a rod 93 to a rocker 94 pivoted at 95 on the frame 5 and having a roller 96 adapted to be engaged by the cam 78. An arm 97 is pivoted at 98 on the frame 65 5 at one side of the rocker 94 and is connected thereto by a spring 99. A roller 100 on the rocker 94 is held in engagement with the arm 97 by the spring 99. When arm 90 is held by the arm 91 as indicated in Figs. 1 and 7 the arm 97 is held by the spring 99 70 out of the path of the tail by the dog 82 and the cam 80 will rotate with the shaft 70. When however, the arm 90 is released by the operation of the selector mechanism which depresses the arm 91 and thereby 75 moves it from the path of the arm 90, the latter will be permitted to swing to the right and the rocker 94 will also swing to the right viewing Fig. 8 carrying the arm 97 into the path of the tail of the dog 82 80 thus releasing the dog from its notch and uncoupling the cam 80 from the shaft 70.

Supported in axial alinement with the rocker 94 is a rocker 101 (Fig. 9). An arm 102 is supported in axial alinement with the 85 arm 97 at one side of the rocker 101 and is connected to the latter by a spring 103 which holds a roller 104 on the rocker 101 in engagement with the arm 102. Normally the rocker is so positioned that the arm 102 90 is out of the path of the tail of the dog 83 on the cam 81. However, when the cam 80 comes to rest in the manner just described a high portion thereon engages a roller 105 on the rocker 101 swinging the latter on 95 its pivot and moving the lever 102 into the path of the tail of the dog 83. Upon continued rotation of the shaft 70 the tail of the dog 83 engages the lever 102 thereby withdrawing the dog from its notch and 100 uncoupling the cam 81 from the shaft 70. The uncoupling occurs just as the roller 88 drops into the depression following the high point of the cam and the gate 37 is moved to the right viewing Fig. 5 and held there 105 during the following revolution of the shaft 13 or while a printing device is discharged into the chute 36 and thence to the tray 40.

The above described operation occupies 110 two complete revolutions of the shaft 13 so that the printing device which coöperated with the selector mechanism to release the arm 90 is moved to printing position, printed and discharged into the proper 115 tray. Meanwhile upon the first revolution of the shaft following the release of the arm 90, a high point on the cam 78 engages the roller 96 on the rocker 94 and swings the rocker to the left viewing Fig. 3. A corresponding movement of the arm 90 permits the arm 91 which is spring actuated to move upwardly to its normal or set position. The lever 97 is withdrawn from the path of the tail of the dog 82 and consequently upon the following revolution of the notched collar 76 the dog 82 drops into the notch to again lock the cam 80 to the shaft 70. Movement of the cam 80 withdraws the high portion thereof from engagement with 125 130

the roller 105 permitting the arm 102 to swing out of the path of the tail of the dog 83 which is again permitted to engage the notch in the collar 77 locking the cam 81 to the shaft 70. The normal operation permitting delivery of printing devices to the tray 41 is then continued until the selector mechanism again releases the arm 90.

The selector mechanism which controls the 10 the previously described operation comprises a selector frame 107 pivoted at 108 on the frame 5 of the machine and extending across the path of the printing devices between inking and printing position. A selector bar 15 109 is pivotally mounted on the frame 107 and extends across the path of the printing devices in front of the frame. This bar carries the arm 91 previously described and is connected to the frame 107 by a spring 110 so 20 that it normally tends to follow the movement of the frame. The selector bar is provided with a plurality of spaced openings (Fig. 1) to receive one or more pins 111 (Fig. 7).

25 The selector frame is normally sustained to elevated position by a spring pressed plunger 112 which engages the frame 5 of the machine. To effect depression of the selector frame and bar I provide a cam track 30 113 on the frame in the path of a depressor device 114 pivotally mounted at 115 on an arm 116 connected to one of the arms 32 of the rocker 26. A roller 117 (Fig. 7) on the depression device 114 engages the cam track 35 113 and as the roller rides up the inclined plane of the cam track the selector frame swings downwardly about its pivot carrying the selector bar therewith.

Each printing device 7 is provided with 40 a tab 118 which may be adjustably disposed in one of a plurality of positions in a manner well understood in the art. If the tab 118 on the particular printing device which is beneath the selector bar is not in the 45 path of the pin 11 thereon the selector bar travels downwardly with the selector frame and the operation of the machine is normal. The printing device then passes into the tray 41. If however, the tab 118 is in the path 50 of the pin downward movement of the selector bar is limited thereby and as the selector frame descends the selector bar swings on its pivot relative to the selector frame causing the arm 91 to disengage the arm 90, 55 which then swings forwardly in the manner previously described to initiate the operation of the cams 80 and 81 resulting in delivery of the printing device to the tray 40.

As an example of the operation we may 60 assume that all printing devices bearing addresses of subscriptions expiring in December have tabs disposed in the same relative positions. When the December issue of the periodical or the wrappers therefor are 65 printed the pin 111 is so disposed in the

selector bar as to engage the tabs of these printing devices. Consequently all printing devices having tabs in the December position will be separated from the others and deposited in the tray 40. Thus expiring 70 subscriptions are automatically eliminated from the series of printing devices. While this is one practical and desirable use for my invention it is of course not limited thereto. 75

Nor is it limited to the specific embodiment illustrated since obviously various changes may be made in the form, construction and arrangement of the parts without departing from the spirit and scope of the 80 invention or sacrificing any of its material advantages, the form hereinbefore described being merely the preferred embodiments thereof. 85

I claim:

1. In a printing machine, a platen, a magazine, means for moving printing devices from said magazine to and from printing position beneath said platen, a plurality of receptacles to receive said printing devices, and means for separating said printing devices into classes and selectively delivering the respective classes to separate receptacles including means for initiating the operation of separating the printing devices 90 before the latter are disposed in printing position. 95

2. In a printing machine, a platen, a magazine, means for moving printing devices from said magazine to and from printing position beneath said platen, a delivery chute through which said printing devices normally pass, means for diverting selected printing devices from said chute, and means for initiating the operation of said diverting 105 means before the individual devices are disposed in printing position. 100

3. In a printing machine, a platen, a magazine, means for moving printing devices from said magazine to and from printing position beneath said platen, a delivery chute through which said printing devices normally pass, a branch chute, means for diverting selected printing devices into said branch chute, separate receptacles to receive 110 said printing devices from the respective chutes, and means for initiating the operation of the diverting means before the individual printing devices are disposed in printing position. 115

4. In a printing machine, a platen, a magazine, means for moving printing devices from said magazine to and from printing position beneath said platen, a plurality of receptacles to receive said printing devices, and means including a plurality of chutes and guiding means to selectively deliver said printing devices to separate receptacles, and means for controlling said guiding means including means for initiat- 120 125 130

ing the operation of said controlling means before the individual printing devices are disposed in printing position.

5. In a printing machine, a platen, a magazine, means for moving printing devices from said magazine to and from printing position beneath said platen, a plurality of receptacles to receive said printing devices, and means adapted to engage said printing devices before they reach printing position and influenced by the characteristics of individual printing devices to control the delivery thereof to one or the other of said receptacles.

15 6. In a printing machine, a platen, a magazine, means for moving printing devices from said magazine to and from printing position beneath said platen, a plurality of receptacles to receive said printing devices, chutes leading thereto and means adapted to engage said printing devices before they reach printing position and influenced by the characteristics of the individual printing devices to control delivery 25 thereof to one or the other of said chutes.

7. In a printing machine, a platen, a magazine, means for moving printing devices from said magazine to and from printing position beneath said platen, a plurality 30 of receptacles to receive said printing devices and means adapted to engage said printing devices before they reach printing position and influenced by the characteristics of an individual printing device to control delivery of the latter after it has passed the printing position to one or the other of 35 said receptacles.

8. In a printing machine, a platen, a magazine, means for moving printing devices from said magazine to and from printing position beneath said platen, a plurality 40 of receptacles to receive said printing devices, a selector mechanism coöperating with the individual printing devices before they are disposed in printing position to detect 45 the predetermined classification thereof, and means controlled thereby to selectively direct said printing devices according to class into the respective receptacles after leaving 50 printing position.

9. In a printing machine, a platen, a magazine, means for moving printing devices from said magazine to and from printing position beneath said platen, a pair of 55 receptacles to receive said printing devices, a pair of chutes leading to said receptacles, a gate to direct said printing devices in said respective chutes and a selector mechanism coöperating with individual printing devices 60 before they are disposed in printing position to detect the predetermined classification thereof, and means controlled thereby to actuate said gate.

10. In a printing machine, a platen, a magazine, means for moving printing de-

vices from said magazine to and from printing position beneath said platen, means co-operating with each printing device before it is disposed in printing position to detect the predetermined classification thereof, and 70 means operative after the printing operation to separate said printing devices in accordance with said classification.

11. In a printing machine, a platen, a magazine, means for moving printing devices from said magazine to and from printing position beneath said platen, receptacles to receive different classes of said printing devices, means in the path of said printing devices as they are moved to printing position for detecting the predetermined classification of said printing devices, and means operative after the printing operation for separating said printing devices and depositing said classes in the respective receptacles. 80

12. In a printing machine, a platen, a magazine, means for moving printing devices from said magazine to and from printing position beneath said platen, receptacles to receive different classes of said printing devices, a selector mechanism adapted to engage the printing devices before they reach printing position and influenced by the individual characteristics thereof and means controlled thereby for subsequently separating 90 said printing devices according to said characteristics and delivering them to the respective receptacles.

13. In a printing machine, a platen, a magazine, means for moving printing devices step by step from said magazine to and from printing position beneath said platen, a pair of receptacles for said printing devices, chutes leading to said receptacles, a gate for directing said printing devices into 105 one or the other of said chutes, means for actuating said gate and means coöperating with individual printing devices before they reach printing position to control said actuating means. 110

14. In a printing machine, a platen, a magazine, means for moving printing devices from said magazine to and from printing position beneath said platen, receptacles to receive said printing devices, means for controlling movement of said printing devices to the respective receptacles including a selector frame, a selector bar supported on and movable conjointly with and relatively to said frame, and means adjustably 115 supported on said bar and adapted to engage printing devices having predetermined characteristics. 120

15. In a printing machine, a platen, a magazine, means for moving printing devices from said magazine to and from printing position beneath said platen, receptacles to receive said printing devices, a selector mechanism including a selector frame and a selector bar supported on and movable con- 125 130

jointly with and relatively to said frame, and means adjustably supported on said bar and adapted to engage printing devices having predetermined characteristics, and 5 means controlled thereby to subsequently direct the printing devices into the respective receptacles.

16. In a printing machine, a platen, a magazine, means for moving printing devices from said magazine to and from printing position beneath said platen, receptacles to receive said printing devices, a gate to direct the movement of said printing devices into the respective receptacles, means for 10 operating said gate comprising a constantly driven shaft, a cam loosely supported on said shaft, means connected to said gate and operable by said cam, a releasable driving connection between said cam and shaft and 15 means for controlling said connection.

17. In a printing machine, a platen, a magazine, means for moving printing devices from said magazine to and from printing position beneath said platen, receptacles 20 to receive said printing devices, a gate to direct the movement of said printing devices into the respective receptacles, means for operating said gate comprising a constantly driven shaft, a cam loosely supported on each shaft, means connected to said gate and operable by said cam, a releasable driving connection between said cam and shaft and means for controlling 25 said connection including a selector adapted 30 to coöperate with printing devices having predetermined characteristics.

18. In a printing machine, a platen, a magazine, means for moving printing devices from the magazine to and from printing position beneath said platen, receptacles 35 to receive said printing devices, a gate to direct the movement of said printing devices into the respective receptacles, means for op- 40

erating said gate comprising a constantly driven shaft, two cams loosely mounted on 45 and normally connected to said shaft, means connected to said gate and engaging one of said cams, and means for successively disconnecting said cams from said shaft.

19. In a printing machine, a platen, a magazine, means for moving printing devices from the magazine to and from printing position beneath said platen, receptacles to receive said printing devices, a gate to direct the movement of said printing devices 50 into the respective receptacles, means for operating said gate comprising a constantly driven shaft, two cams loosely mounted on and normally connected to said shaft, means connected to said gate and engaging one of 55 said cams, and means for successively disconnecting said cams from said shaft including a selector adapted to coöperate with printing devices having predetermined characteristics. 65

20. In a printing machine, a platen, a magazine, means for moving printing devices from the magazine to and from printing position beneath said platen, receptacles to receive said printing devices, a gate to 70 direct the movement of said printing devices into the respective receptacles, means for operating said gate comprising a constantly driven shaft, two cams loosely mounted on and normally connected to said 75 shaft, means connected to said gate and engaging one of said cams, and means for successively disconnecting said cams from said shaft and means for automatically reëstablishing the connection between said shaft and 80 cams. 75
